INVENTOR,
Lewis F. Davis,
By Martin P. Smith Atty

UNITED STATES PATENT OFFICE.

LEWIS F. DAVIS, OF LOS ANGELES, CALIFORNIA.

METHOD OF AND APPARATUS FOR SPIRALLY WINDING WIRE ON TUBES.

Application filed February 11, 1926. Serial No. 87,492.

My invention relates to a method of and apparatus for spirally winding wire on tubes, the principal objects of my invention being to provide a relatively simple, easily practiced, and economical method for arranging or winding wire or the like spirally upon elongated cylindrical or tubular members, and further to provide a relatively simple form of apparatus that may be advantageously used for practicing my improved method.

In certain types of water heaters, and especially those used for household water heating purposes, circulation tubes having spirally disposed ducts or water passageways are used and it is the purpose of my invention to provide simple means whereby a wire-like member may be spirally disposed on the surface of a tube in order that when said tube carrying said spirally disposed member is encased in a jacket or outer tube, the spirally disposed duct or passageway between the two tubes will form a relatively narrow spirally disposed chamber through which water may circulate while being heated.

With the foregoing and other objects in view, my invention consists in certain novel features of construction and arrangement of parts that will hereinafter be more fully described and claimed and illustrated in the accompanying drawing, in which—

Fig. 1 is a side elevational view, partly in section, of an apparatus embodying my invention and which is particularly designed for practicing my improved method.

Fig. 2 is a perspective view of the die through which the wire passes while being spirally arranged on the tube.

Fig. 3 is a vertical section taken lengthwise through the center of the die.

Fig. 4 is a cross-section taken on the line 4—4 of Fig. 3.

Fig. 5 is an elevational view of the head that is carried by the end of the spindle and which clamps the wire that is applied to the tube.

Fig. 6 is a cross-sectional view taken approximately on the line 6—6 of Fig. 5.

Fig. 7 is a cross-sectional view taken approximately on the line 7—7 of Fig. 5.

Fig. 8 is a horizontal section taken on the line 8—8 of Fig. 5.

Fig. 9 is an elevational view of a portion of a tube with a wire spirally arranged thereupon in the manner provided for by my invention.

Referring by numerals to the accompanying drawing which illustrates a simple and practical apparatus for practicing my improved method, 10 designates a base member that is similar to the bed plate of a lathe, and arranged for rotation in a suitable bearing 11 on said base is a spindle 12 that may be driven in any suitable manner and which spindle carries a removable head 13 that is substantially cylindrical in form and which is provided adjacent to its outer end with a circumferentially disposed shoulder 14.

Detachably seated in the outer end of head 13 is one end of a rod 15, and fixed in any suitable manner on the outer end of this rod is a short cylindrical head 16. Formed in the inner face of head 16 to one side of the opening therethrough that receives rod 15 is a substantially V-shaped notch 17, one of the faces of which is provided with teeth or corrugations 18.

Arranged on rod 15 immediately adjacent the head 16 is a short cylindrical head 19 that is provided on one end with a circumferentially disposed shoulder 20, and on the opposite end with an outwardly projecting V-shaped lug 21 that is adapted to enter notch 17 in head 16. Head member 19 is connected to member 16 by means of longitudinally disposed bolts or screws 22. One of these screws is located on the opposite side of the axis of the head from the notch 17 and arranged in a pocket 23 in head member 19 below the head of this screw is a relatively stiff compression spring 24 that normally exerts outward pressure against the head of said screw thereby causing the latter to function as a balance screw 25 when the end of a section of wire or the like is clamped in the notch 17 by lug 21.

Arranged to slide lengthwise in suitable guideways on top of base 10 is a plate 25 and formed on the top thereof is a transversely disposed saddle 26 for a short tubular die-holding member 27. This member 27 is screw-held in position on the saddle 26 by means of an inverted U-shaped strap 28 the lower ends of which are bolted to the saddle and the upper part of said strap car-

rying a large set-screw 29 that bears on the upper portion of member 27.

Seated in tubular member 27 is the wire winding die, the same comprising a short tubular member 30 having formed in its wall a spirally disposed slot 31 and which latter is formed so that it makes at least one complete turn in the length of the tubular die. This die is firmly secured within the holding member 27 by means of set-screws such as 32. The die-carrying base plate 25 is moved lengthwise on bed plate 10 by a suitable feeding mechanism under control of a crank or hand wheel such as 33.

15 In practicing my improved method with the apparatus herein shown and described, the removable head comprising members 16 and 19 is removed from the end of shaft 15 and tube T that is to receive the spirally disposed wire is positioned lengthwise over shaft 15 with one end of said tube bearing against shoulder 14 of head 13. Head member comprising parts 16 and 19 is now positioned on the outer end of rod 15 and after 20 the outer end of the tube is engaged against shoulder 20 and one end of the wire W is positioned between lug 21 and the toothed face of notch 17, the parts of this head are securely fastened to each other by tightening 25 the bolts 22 and by setting the screws or nuts that lock member 16 to the rod.

The die-holding base plate 25 is now moved toward the tube and wire carrying parts and when head member 16 has entered 30 the die 30, the end of wire W adjacent to the head comprising the parts 16 and 19 will enter the inner end of the spirally disposed slot 30 in die 31. Rotary motion is now imparted to spindle 12 with the result that 35 head 13, shaft 15, outer head comprising the parts 16 and 19, and the supported tube T will be rotated and the engagement of the wire in the spirally disposed slot 31 of the die will cause the latter to travel lengthwise 40 of the tube T toward the inner head 13 and as a result, the wire will be spirally disposed upon the surface of said tube.

45 After the die has moved to the inner end of the tube, that portion of the wire on the tube that projects through the die may be secured to said tube by the application of 50 solder or by spot welding, after which the outer head member comprising the parts 16 and 19 is removed from the shaft 15 and thereby enabling the tube with wire spirally 55 disposed thereupon and secured thereto to be removed from the supporting shaft 15 and the die.

60 Thus it will be seen that I have provided relatively simple and easily operated means and an easily practiced method for spirally winding wire, or wire-like strips of metal on the surfaces of tubes, cylinders, and the like.

65 It will be understood that the structure of

the apparatus herein shown and described may be modified in certain details without departing from the spirit of my invention, the scope of which is set forth in the appended claims.

70

I claim as my invention:

1. The herein described method of spirally winding wire upon tubes, which consists in simultaneously rotating a tube and wire and causing the same to pass lengthwise 75 through a non-rotating die that is provided with a spirally disposed slot that receives and bends said wire as the same and the tube pass through said die.

2. The herein described method of spirally winding wire upon tubes, which consists in mounting a tube and wire on a rotatable support, then rotating said support so as to simultaneously rotate said tube and wire and applying pressure to said wire so as to cause 85 the same to be bent in spiral arrangement upon the surface of said tube.

3. The herein described method of spirally winding wire upon tubes, which consists in mounting a tube and wire on a rotatable 90 support, then rotating said support so as to simultaneously rotate said tube and wire and applying pressure progressively lengthwise of said wire so as to cause the same to wind spirally upon the surface of said 95 tube.

4. In an apparatus for spirally winding wire upon tubes, means for supporting and simultaneously rotating a tube and wire and means movable toward said supporting 100 means and through which said tube and wire are adapted to pass for winding the wire spirally upon the surface of said tube.

5. In an apparatus for spirally winding wire upon tubes, means for supporting and 105 simultaneously rotating a tube and wire, a die movable toward and away from said supporting means and through which die the tube and wire are adapted to pass and which die is provided with a spirally disposed wire-receiving slot.

6. In an apparatus for spirally winding wire upon tubes, a rotary supporting member, means on said member for clamping a tube and wire, a die mounted to move lengthwise of said supporting member and which die is provided with a wire-receiving slot that is arranged so that the wire in passing therethrough is spirally disposed upon the 115 surface of the tube.

7. In an apparatus for spirally winding wire upon tubes, the combination with a tubular die having an internally arranged wire-receiving slot, of a combined tube and wire-supporting spindle adapted to pass 125 through said die.

8. In an apparatus for spirally winding wire upon tubes, a spindle comprising a shaft, a pair of heads carried by said shaft, which heads are adapted to engage and sup- 130

port a tube, and means on one of said heads for clamping a section of wire.

9. In an apparatus for spirally winding wire upon tubes, a spindle, means carried by said spindle for supporting and clamping a tube and a section of wire, a non-rotating die

of wire are adapted to pass and which die is provided with a spirally disposed slot that receives the wire as said die is moved longitudinally relative to the tube and its support. ¹⁰

In testimony whereof I affix my signature.

LEWIS F. DAVIS.
